MECHANISM TO SECURE STEREOGRAPHIC PRINTING PLATES AND IN PRINTING PLATES FOR USE WITH THAT MECHANISM

John Oldfield Crabtree and Charles William Marshall, London, England, assignors to R. Hoe & Co. Inc., New York, N. Y., a corporation of New York

Application January 10, 1950, Serial No. 137,861
In Great Britain January 10, 1949

6 Claims. (Cl. 101—378)

1

This invention relates to mechanism to secure stereotype printing plates to the cylinders of rotary printing machines and to stereotype plates themselves.

The invention is concerned with the type of holding mechanism which is arranged to tension the plate from its ends circumferentially of the cylinder for which purpose the undersurface of the plate is formed in one or other fashion to be engaged by clamps along a line parallel with its ends and which are movable in the circumferential sense.

In a large class of rotary printing machines using such plates, the plates often extend over a considerable arc say about 180° of the cylinder. To afford the desired purchase of the clamps on the plate, it is necessary to provide both the plate and the clamps with undercut surfaces which have to be moved clear of one another when the plate is presented to the cylinder for the plating operation and when the plate is to be removed from the cylinder.

The main object of this invention is to provide a plate-holding mechanism and a plate which will facilitate the fitting to and removal of the plate.

This object is achieved broadly stated by providing the clamp for at least one of the ends of the plate with plate-engaging surfaces which are spaced apart in the longitudinal sense of the cylinder and by forming the plate with correspondingly spaced surfaces, the spacing of the surfaces on the clamp and the plate being such that those on the plate can intercalate those on the clamp: with this arrangement, the plate can readily be presented so to speak, face-on to the cylinder in the intercalating relationship and then slid longitudinally of the cylinder to bring its clamping surfaces into operative register with the clamping surfaces of the clamp which can then be operated to effect the desired tensioning of the plate about the cylinder. The converse operation is carried out when the plate is to be removed.

When a plate is to be engaged only at its leading and trailing ends, it would be sufficient for the clamp and the plate to be formed in accordance with this invention at only one end although if desired both the leading and trailing ends and their clamps could be so formed.

The invention is concerned also with the use of a very common type of printing plate having at

2

its under or concave surface circumferential ribs, and the invention contemplates forming in such ribs undercut recesses to form the clamping surfaces to be engaged in the region of the leading and trailing edges by clamps which can be moved to tension the plate circumferentially of the cylinder. When the clamping mechanism is constructed according to the feature of this invention as first referred to (i. e. with clamping surfaces arranged to intercalate those on the plate) then the clamp would be formed with clamping surfaces which are spaced apart to enable the circumferential ribs to be passed between them, the plate then being moved longitudinally to cause the surfaces on the clamp to pass into the recesses in the ribs.

The use of the ribs to afford the desired clamp-engaged surface enables a plate as produced by the widely used plate casting equipment to be modified for the purpose of the present invention by a simple machining operation by which the recesses are cut transversely in the circumferential ribs as produced by those machines.

The clamps for both the leading and trailing edges of such a plate could be formed merely by bars having undercut or hooked-shaped faces and extending longitudinally of the cylinder and one at least of these bars is movable in the circumferential sense of the cylinder to tension and release a plate.

One or both of the bars is notched at a pitch related to the pitch of the circumferential ribs on the plate, the notches being dimensioned to receive the ribs whereafter as has been described the plate is moved longitudinally to carry the end undercut walls of the recesses formed in the ribs into register with the projections left between the notches on the bar.

The invention is illustrated in the accompanying drawings as applied to the plate securing mechanism forming the subject of the pending application Serial No. 137,862. In the drawings, Figure 1 is an end elevation of a printing cylinder having a printing plate secured to it. Figure 2 is a longitudinal sectional elevation on the line I—I, Figure 1, showing only part of the total length of a printing cylinder. Figure 3 is a perspective view showing part of a printing cylinder and a printing plate prepared for use with the clamping mechanism. Figure 4 is a local elevation looking in the direction of the arrow IV, Figure 1, the

figure being partly in section with parts broken away, and Figure 5 a section on the line V—V, Figure 4.

Reference will first be made to the plate securing mechanism so that the purpose of the present invention shall be more readily understood.

Referring firstly to Figures 1 and 3, 1 indicates a printing cylinder and 2 a stereotype printing plate fitted thereto, the plate having at its under surface (i. e. its concave surface) a series of circumferential ribs 3. These ribs are cut away to form recesses 4 and 5 near the longitudinal edges of the plate and to leave at the longitudinal centre of the plate a series of projections 6, the walls of the recesses 4 and 5 and of the projections being undercut or sloped.

The cylinder 1 is fitted with clamping mechanism comprising intermediate clamps to engage or grip the projections 6 and clamps (or hooks) to engage in the recesses 4 and 5 to tension the plate circumferentially about the cylinder from the gripped projection 6.

The intermediate clamp comprises a fixed bar 7 having an upstanding hook-shaped part 8 to engage one undercut wall of the projection 6, a movable bar 9 also having an upstanding hook-shaped part 10 to engage the other undercut wall of the projection 6. The fixed bar 7 is disposed towards the trailing end of the plate 2 (it being assumed that the cylinder 1 will rotate in the direction of the arrow II in Figure 1) while the movable bar 9 is disposed towards the leading end, and this movable bar is arranged to be operated to move in a direction towards the trailing end of the plate and hence towards the fixed bar 7 and so, conjointly with the fixed bar, to embrace and grip the dovetail projection 6. This results in anchoring the plate to the cylinder 1 against both circumferential and radial movement.

Each of the end clamps is similar and each comprises a bar 12 having hook-shaped projections 13 to engage the undercut walls of abutments formed by the recesses 4 and 5 at the leading and trailing edge respectively. Each bar is movable in the generally circumferential sense of the cylinder towards and away from the intermediate clamp, 8, 10.

Assuming that the intermediate clamp has been operated to take hold of the projection 6 at the center of the plate 3, the end clamp bars 12 at the leading and trailing edges of the plate are operated to strain or tension the plate away (in each direction about the cylinder) from the intermediate clamp which provides a fixed reaction point to the tensional strain.

Considering now the present invention it will be clear that in fitting a plate 2 to a cylinder 1 the undercut walls of the recesses 4, 5 have to pass over the hooked ends 13 of the clamping bars 12, and the purpose of the present invention is to facilitate this operation especially in those cases in which the plate 2 extends over a substantial arc of a circle.

For the purpose of this invention, the clamping bars 12 instead of being formed with a continuous hook surface are formed with spaced hook portions 13 which leave gaps 30. The gaps have a pitch corresponding to the pitch of the ribs 3 of the plate 2. With this arrangement, the plate 1 can be presented face-on to the cylinder with the gaps 30 in register with the ribs 3 as shown in Figure 2. The plate is then slid longitudinally up to a margin ring 31 so as to bring the hook portions 13 left by the gaps 30 into lon-

gitudinal register as shown in Figure 4 with the ribs 3 or more precisely with the abutments formed by the recesses in the ribs.

It is to be pointed out that the intercalating arrangement of this invention is not limited in its application to the plate clamping arrangement shown in the drawings: i. e. it is not limited to an arrangement employing the intermediate plate clamp 7, 9 for it could be applied to an arrangement employing only the end components 12. However, when such a central clamp is used it is not necessary to form the clamp bar 9 in this way for the projections 6 on the plate can pass straight in between the hooks 8 and 10 when the hook 10 is retracted.

It is also to be observed that while it is preferred to arrange both components 12 with the gaps 30, it is not essential for more than one of them so to be formed. In such a case, the recesses 5 at one edge of the plate 2 could be hooked under the ungapped hook 12 and then rocked to bring its other recesses 5 into the gaps 30 of the other component 12 and then slid longitudinally.

The various operating bars are arranged for actuation from the ends of the cylinder 1 and the actuating mechanism would include a spring or springs which would operate to urge the clamps to be spring held against their respective surfaces on the plate.

In the arrangement shown in the drawing and especially in Figures 2, 4 and 5, the two clamping bars 12 and the clamping bar 9 are similar as regards their operating mechanism and in Figures 2, 4 and 5 this is indicated by the combined references 12 (9) and 13 (10).

Each of the bars is flanged at 14 and is secured to a plate 15 which together with the flanges 14 are slideable in longitudinal recesses 16 in the cylinder 1, the direction of sliding movement being tangential of the cylinder. One edge of the plate 15 is formed with a series of wedge surfaces 17 along its length. Cooperating with these surfaces are other wedge surfaces 18 on an operating bar 19 which is slideable longitudinally in the recess 16. Hence by moving the bar 19 forwards or backwards, the clamping bars 9 and 12 are caused to move backwards or forwards tangentially of the cylinder so as either to thrust the hooks 10 or 13 against the abutment surfaces on the plate or to retract them from those surfaces.

The wedges would be arranged at such an angle as to be irreversible so that the operating bars cannot be reversed by reaction from the plate 2.

In order that clamping bars 12 shall be spring pressed so as automatically to take-up any increase in the arcuate length of the plate and also in the case of the bars 9 and 12 to accommodate for differences in various plates, the operating bars 19 are bored at one end to receive a coil spring 20 which acts and reacts between the bar 19 and a plunger rod 21 which is pivotally connected at 22 to a link 23. The link is pivoted at 24 to an operating bell crank 25 pivoted at 26 in a bracket 27 secured to the end of the cylinder 1, the bell-crank having an operating arm 28. When the bell-crank lever 25 is rocked, the corresponding bar 19 is moved backwards or forwards. When, in moving forwards, the wedges 18 thrust the hooks against the abutments on the plate 1 so that the hooks meet with resistance, the continued movement of the bell-crank 25 causes the spring 20 to be compressed and to

urge the hooks forward by their spring pressure. The arrangement of the pivoted centres 22, 24 and 26 is such that the final movement of the bell-crank 25 carries the centre 24 past the straight line joining the centres 22 and 26, i. e. it carries the bell-crank to an over-centre position so that the spring 20 now reacts to hold the bell-crank 28 locked in its clamping position and at the same time to urge the hooks forwardly against the plate.

The pivotal connection 22 between the link 23 and the bar 19 is effected through a slot 29 in the bar 19. The slot enables the bar 19 to have freedom to be urged forward by the spring 20 without restraint by the operating bell-crank and (when the bell-crank is reversed to release the bar 19) the pin travels to the end of the slot and then positively moves the bar.

By reason of the irreversibility of the bar 9 of the intermediate clamp, a reaction is provided against which the action of the spring 20 of the clamp for the leading end of the plate can exert circumferential tension in a direction towards the leading end of the plate.

We claim:

1. In combination a printing cylinder, a curved stereotype printing plate having ribs on its concave surface and undercut abutments formed in the ribs at the trailing and leading edge regions of the plate, plate clamping mechanism comprising angularly separated plate clamps having hook shaped members projecting beyond the periphery of the cylinder to engage respectively the abutments on the plate, and means to move the clamps relatively to tension the plate about the cylinder, said members and the corresponding abutments having cooperating engaging surfaces of less width than the longitudinal spacing between said surfaces, so that the surfaces on the plate can be passed between the surfaces on the clamp and the plate can then be moved longitudinally of the cylinder into register.

2. In combination a printing cylinder, a curved stereotype printing plate having ribs on its concave surface and angularly separated undercut longitudinal abutments formed in the ribs, plate clamps having hook shaped members projecting beyond the periphery of the cylinder to hold a plate to the cylinder by engaging with the abutments, and means to move angularly the said clamps relative to one another to tension the plate between them, said members and the corresponding abutments having cooperating engaging surfaces of less width than the longitudinal spacing between said surfaces, so that the surfaces on the plate can be passed between the surfaces on the clamp and the plate can then be moved longitudinally into register therewith.

3. In combination a printing cylinder, a curved stereotype printing plate having peripherally extending ribs on its concave surfaces with continuous channels cutting across the ribs near the trailing and leading edge regions of the plate thereby forming clamping abutments, plate clamping mechanism in the cylinder and comprising angularly separated plate clamps having abutment engaging members projecting beyond the periphery of the cylinder to engage respectively the abutments on the plate, and means to move the clamps relatively to tension the plate about the cylinder, the said moving means comprising an operating member, and spring means through which the member operates to impart relative tensioning movement to the clamps, and said members and the corresponding abutments

having cooperating engaging surfaces of less width than the longitudinal spacing between said surfaces, so that the abutment surfaces on the plate can be passed between the abutment engaging members on the clamp, and the plate then be moved longitudinally into register.

4. In combination a printing cylinder, a curved stereotype printing plate having peripherally extending ribs on its concave surface with a continuous channel cutting across the ribs near each straight edge of the plate and thereby forming a clamping abutment, plate clamps in the cylinder having abutment engaging members projecting beyond the periphery of the cylinder to hold a plate thereon by engaging with the abutments, and means to move the said clamps relative to one another to tension the plate between them, the said moving means comprising an operating member, and spring means through which the member operates to impart relative tensioning movement to the clamps, the said members and the corresponding abutments having cooperating surfaces of less width than the longitudinal spacing between said surfaces, so that the abutment surfaces on the plate can be passed between the abutment engaging members on the plate and the plate then moved longitudinally into register.

5. In combination a printing cylinder, a curved stereotype printing plate having peripherally extending ribs on its curved surface with a continuous channel cutting across the ribs near the trailing and leading edge regions of the plate thereby forming clamping abutments, plate clamping mechanism in the cylinder and comprising angularly separated plate clamps having abutment engaging members projecting beyond the periphery of the cylinder to engage respectively the abutments on the plate and means to move the clamps relatively to tension the plate about the cylinder, the said moving means comprising an operating member, an irreversible device to transmit plate tensioning operation to the plate clamps, and spring means through which the operating member operates the irreversible device, and at least one of the clamps and the corresponding clamping abutments having cooperating surfaces of less width than the longitudinal spacing between said surfaces, so that the abutment surfaces on the plate can be passed between the abutment engaging members on the clamp, and the plate then be moved longitudinally into register.

6. In combination a printing cylinder, a curved stereotype printing plate having peripherally extending ribs on its curved surface with continuous channels cutting across the ribs near each straight edge of the plate and thereby forming clamping abutments, plate clamps in the cylinder having abutment engaging members projecting beyond the periphery of the cylinder to hold a plate thereon by engaging with the abutments, and means to move angularly the said clamps relative to one another to tension the plate between them, the said moving means comprising an operating member, an irreversible device to transmit plate tensioning operation to the plate clamps, and spring means through which the operating member operates the irreversible device, and at least one plate clamp and its corresponding abutments having cooperating surfaces of less width than the longitudinal spacing between said surfaces, so that the abutment engaging members on the clamp can be passed between

the surfaces on the plate and the plate then moved longitudinally into register.
